O. I. JUDELSHON.
PROTECTOR FOR TRANSMITTING MECHANISM,
APPLICATION FILED JULY 9, 1918.

Patented Nov. 26, 1918.

UNITED STATES PATENT OFFICE.

OSCAR I. JUDELSHON, OF BROOKLYN, NEW YORK.

PROTECTOR FOR TRANSMITTING MECHANISM.

1,285,725.

Specification of Letters Patent. Patented Nov. 26, 1918.

Application filed July 9, 1918. Serial No. 244,053.

To all whom it may concern:

Be it known that I, OSCAR I. JUDELSHON, a citizen of the United States, and resident of New York city, borough of Brooklyn, in the county of Kings and State of New York, have invented certain new and useful Improvements in Protectors for Transmitting Mechanism, of which the following is a specification.

Protecting devices for mechanisms are frequently installed in factories to protect the operatives from such mechanisms, and this is particularly applicable to the so-called transmitting-mechanisms used in conjunction with power operated sewing machines, especially where a number of such sewing machines and transmitting mechanisms are arranged side by side upon a long table. When it is desired to adjust the transmitting mechanism, such as by removing or applying the belt, etc., the operator removes the protector and sometimes does not readjust the protector to its proper position, thereby leaving the mechanism unprotected.

The object of my invention is to provide a simple and cheap protector for such mechanism, adapted to be retained in a position to protect the mechanism and so arranged that the protector will automatically return to its protecting position over the mechanism and will be there retained.

A further object of the invention is to provide means whereby if the protector should remain away from the mechanism and the machine should be operated, such mechanism will coöperate with the protector in such a manner as to cause the protector to be vibrated or shaken, thereby to produce an audible signal to apprise the operator that he should restore the protector to its protecting position.

My invention comprises a protector adapted to be retained in a protecting position over a transmitting mechanism, such as pulleys and belts, said protector being of such a character as to produce an audible signal or sound when vibrated or shaken, with means to automatically restore the protector to its protecting position over the mechanism and at the same time so retain the protector as to prevent its vibration or shaking so as not to produce an audible sound. Means are also carried by the protector and coöperative with said mechanism, such as with one of said belts, to cause vibration or shaking of the protector and consequent

production of an audible signal when the belt is operated and the protector is in the non-protecting position, whereby when the protector is in the protecting position said means will not coöperate with said belt, and no signal will be produced.

My invention comprises novel details of improvement and combinations of parts that will be more fully hereinafter set forth and then pointed out in the claims.

Reference is to be had to the accompanying drawings forming part hereof, wherein:

Figure 1 is a partly sectional side elevation illustrating a transmitting mechanism and my improved protector associated therewith, which protector is in the non-protecting position exposing the mechanism; Fig. 2 is a sectional view substantially similar to Fig. 1, showing the protector in the protecting position; Fig. 3 is a cross section substantially on the line 3, 3, in Fig. 1; and Fig. 4 is a detail perspective view of my improved protector.

Similar numerals of reference indicate corresponding parts in the several views.

My improved protector may be applied in conjunction with any suitable transmitting or power mechanism 1 for protecting the same. In the example illustrated the transmitting mechanism comprises a hanger or bracket 2, having a shaft 3 loosely carrying a pulley 4 over which passes a transmitting belt 5 adapted to operate a sewing machine or other machine which may be mounted upon table 6 in any well known manner. Hanger or bracket 2 hangs from the table. Secured upon shaft 3 is a stepped or cone-pulley 7 adapted to receive a power driven belt 8 from a source of power in a well known manner. Clutch mechanism for causing pulley 7 to operate pulley 4 may be provided in any usual manner, such as by means of a lever 8 pivoted at 10 and provided with an operating arm 11, whereby the depending arm 12 may be actuated to cause the cone-pulley to be pushed toward and from the transmitting pulley. The foregoing parts are merely illustrative of a transmitting mechanism adapted for use with my invention.

My improved protector is indicated generally at 14, and is preferably made of sheet metal pivotally supported by a suitable hinge 15 secured to table 6, so that the protector may hang below the table in position to expose the transmitting mechanism for

attention, as illustrated in Fig. 1, and to be swung into protecting position with respect to said mechanism, as illustrated in Fig. 2. In the form illustrated the protector is in 5 channel-like form, open on one side, to embrace and protect the part of the transmitting mechanism opposing an operator. In the form shown the protector comprises a front wall 16 and side walls 17, 18, projecting therefrom in spaced relation. Wall 16 is shown in annular form extending from a substantially mid-portion 19 so that the upper part of said wall will extend in front of the pulleys and the lower part will incline under the pulleys, in protecting position shown in Fig. 2, and the side walls 17, 18 will extend on opposite sides of the pulleys. The protector may be made from a suitable sheet metal blank cut to the desired 15 shape. For such purpose the mid-portions of the metal of the side walls may be slit and overlapped and fastened together by rivets or the like 20, whereby the members of the protector are braced together. The 20 mid-portion of the wall 18 is preferably cut away or concave at 18^a to afford freedom for the operator to adjust the belts when the protector is hanging from the table, as in Fig. 1. The protector is shown provided 25 with a downwardly extending projection 21, which may be an integral portion of the metal of wall 16, adapted to bear against a stop, such as the usual foot board 22, located beneath the table, whereby the protector will remain properly spaced from the 30 mechanism. A suitable catch device 23 is shown attached to the foot board by a screw or the like 24, being adapted to be placed in front of the projection 21 to retain the 35 protector in its protecting position over the mechanism (Fig. 2), and whereby when said catch is released the protector may swing back from the mechanism. I provide means to automatically restore the protector to its 40 protecting position over the mechanism and to firmly retain the protector in such position so that it will not then vibrate, for which purpose a suitable spring *a* is shown attached at one end to the protector as to a 45 hole *b* in the wall 18, the opposite end of said spring being attached to an abutment, such as the table 6, which may be done by means of a screw-eye *c* attached to the table. The tension of such spring is such that when 50 the protector is released from the position shown in Fig. 1, the spring will draw the protector toward the mechanism and press its projection 21 against the stop or foot board 22, thereby to retain the protector 55 over the mechanism and resiliently press the protector between said stop and the hinge 15, to prevent vibration of the protector, hence preventing an audible signal that would be produced by the vibration of the 60 protector. In case the spring should break 65

or for some other reason the protector should hang from the table, as in Fig. 1, I provide means coöoperative with the mechanism to cause vibration or shaking of the protector for the production of an audible 70 signal from the noise resulting from the shaking of the protector in case the mechanism operates, which means will be out of coöperation with said belt when the protector is adjusted to the mechanism. For 75 such purpose I have shown a projection 25 in the form of a wire loop attached to wall 16 of the protector and receiving the belt 5. The loop-like projection 25 may be secured to wall 16 of the protector as by riveting 80 the ends 26 of the wire of said projection against wall 16, against an interposed plate 27, or the projection 25 may be attached to the protector in any other suitable manner. The length of the projection is such that its 85 end portion 25 will engage the belt when the protector is hanging freely from the table, as indicated in Figs. 1 and 3. At such time the traveling of the belt through and in contact with the projection 25 will cause 90 movement of the latter, and thereby the protector will be vibrated or shaken, and since the protector is made of sheet metal, such vibration or shaking of the protector will produce an audible signal, indicating to the 95 operator that the protector is hanging from its hinge and is not in protecting position over the transmitting mechanism. When the protector is in the last named position (Fig. 2) the belt will run freely through 100 the projection 25 without causing vibration or shaking of the protector and thereby without producing an audible signal.

My invention is simple and cheap to manufacture, yet is effective in use, since 105 the protector may be made in any desired shape to protect the mechanism intended, and merely requires the projection 25 to be operated with a moving part of the transmitting mechanism to cause the production 110 of a desired audible signal.

Having now described my invention what I claim is:

1. The combination of a transmitting mechanism, with a protector movably supported in position to protect the mechanism, and means to automatically restore the protector to such position after having been moved therefrom.

2. The combination of a transmitting 120 mechanism, with a protector movably supported in position to protect the mechanism, and a spring coöoperative with said protector to automatically restore the same to its protecting position over the mechanism and restrain the protector from vibration.

3. The combination of a transmitting mechanism, with a protector movably supported in position to protect the mechanism, means to automatically restore the protector 130

- to such position after having been moved therefrom, and a stop coöoperative with the protector to limit its position respecting the mechanism.
5. The combination of a table, transmitting mechanism hung from the table, a protector for the mechanism hung from the table to swing relatively to the mechanism, and a spring coöoperative with said protector to automatically restore and retain the protector in operating position in front of the mechanism.
10. The combination of a transmitting mechanism having a belt, with a protector movably supported in position to protect said mechanism, said protector having a member adapted to coöperate with said belt for vibrating the protector only when the latter is not in the protecting position with relation to said mechanism.
15. The combination of a transmitting mechanism having a belt, with a protector movably supported in position to protect said mechanism, said protector having a member adapted to coöperate with said belt for vibrating the protector only when the latter is not in the protecting position with relation to said mechanism.
20. The combination of a transmitting mechanism having a belt, with a protector movably supported in position to protect said mechanism, said protector having a loop-like projection receiving said belt therein, said projection being in position to coöperate with said belt for vibrating the protector only when the latter is in non-protecting position with respect to said mechanism.
25. A protector for transmitting mechanism adapted when vibrated to produce a signal, and means coöoperative between said protector and a portion of such mechanism to cause vibration of the protector when said means is actuated by said mechanism.
30. A protector for transmitting mechanism comprising sheet metal having spaced walls to protect said mechanism, said protector having a member coöoperative with a portion of said mechanism when the protector is not in the protecting position to cause vibration of said protector to produce an audible signal.
35. A protector for transmitting mechanism comprising sheet metal in channel-like form open on one side to receive such mechanism therein, and a member carried by said protector and adapted to coöperate with a moving part of the mechanism when the protector is not in the protecting position for vibrating the protector.
40. A protector for transmitting mechanism comprising sheet metal having a wall to oppose the mechanism and spaced walls projecting from the first named wall, the latter wall being in angular form, portions of one of said side walls being secured together, and means to movably support said protector adjacent to the transmitting mechanism, said protector having a member coöoperative with a portion of the transmitting mechanism for vibrating the protector when the latter is not in the protecting position respecting said mechanism.
45. A protector for transmitting mechanism comprising sheet metal having a wall to oppose the mechanism and spaced walls projecting from the first named wall, the latter wall being in angular form, portions of one of said side walls being secured together, and means to movably support said protector adjacent to the transmitting mechanism, said protector having a member coöoperative with a portion of the transmitting mechanism for vibrating the protector when the latter is not in the protecting position respecting said mechanism.
50. A protector for transmitting mechanism comprising sheet metal having a wall to oppose the mechanism and spaced walls projecting from the first named wall, the latter wall being in angular form, portions of one of said side walls being secured together, and means to movably support said protector adjacent to the transmitting mechanism, said protector having a member coöoperative with a portion of the transmitting mechanism for vibrating the protector when the latter is not in the protecting position respecting said mechanism.
55. A protector for transmitting mechanism comprising sheet metal having a wall to oppose the mechanism and spaced walls projecting from the first named wall, the latter wall being in angular form, portions of one of said side walls being secured together, and means to movably support said protector adjacent to the transmitting mechanism, said protector having a member coöoperative with a portion of the transmitting mechanism for vibrating the protector when the latter is not in the protecting position respecting said mechanism.
60. A protector for transmitting mechanism comprising sheet metal having a wall to oppose the mechanism and spaced walls projecting from the first named wall, the latter wall being in angular form, portions of one of said side walls being secured together, and means to movably support said protector adjacent to the transmitting mechanism, said protector having a member coöoperative with a portion of the transmitting mechanism for vibrating the protector when the latter is not in the protecting position respecting said mechanism.
65. A protector for transmitting mechanism comprising sheet metal having a wall to oppose the mechanism and spaced walls projecting from the first named wall, the latter wall being in angular form, portions of one of said side walls being secured together, and means to movably support said protector adjacent to the transmitting mechanism, said protector having a member coöoperative with a portion of the transmitting mechanism for vibrating the protector when the latter is not in the protecting position respecting said mechanism.
70. A protector for transmitting mechanism comprising sheet metal having a wall to oppose the mechanism and spaced walls projecting from the first named wall, the latter wall being in angular form, portions of one of said side walls being secured together, and means to movably support said protector adjacent to the transmitting mechanism, said protector having a member coöoperative with a portion of the transmitting mechanism for vibrating the protector when the latter is not in the protecting position respecting said mechanism.
75. Signed at New York city, in the county of New York and State of New York this 8th day of July A. D. 1918.

OSCAR I. JUDELSHON.
